DESIGN FOR A COMBINATION VEGETABLE PEELER, FRUIT CORER, AND GRAPEFRUIT SECTIONIZER

Nathan K. Morris, Asbury Park, N. J.

Application February 11, 1944, Serial No. 112,540

Term of patent 14 years

(Cl. D22—3)

To all whom it may concern:

Be it known that I, Nathan K. Morris, a citizen of the United States, residing at Asbury Park, county of Monmouth, and State of New Jersey, have invented a new, original, and ornamental Design for a Combination Vegetable Peeler, Fruit Corer, and Grapefruit Sectionizer, of which the following is a specification, reference being had to the accompanying drawing, forming a part thereof.

Figure 1 is a side elevational view of the combination vegetable peeler, fruit corer and grapefruit sectionizer, embodying my new design;

Figure 2 is a front elevational view of the same;

Figure 3 is a rear elevational view thereof;

Figure 4 is a horizontal sectional view as seen on line 4—4 of Figure 2, showing particularly the curvature of that portion of the device embodying the peeler and the cutting edge thereof; and

Figure 5 is a horizontal sectional view as seen on line 5—5 of Figure 3, showing more particularly the curvature of the intermediate portion of the device and the grooves therein.

I claim:

The ornamental design for a combination vegetable peeler, fruit corer, and grapefruit sectionizer, as shown and described.

NATHAN K. MORRIS.
